REFRIGERATOR CAR CONSTRUCTION

Kurt E. Zeidler, Chicago, Ill., assignor to Standard Railway Equipment Manufacturing Company, Chicago, Ill., a corporation of Delaware

Application April 6, 1940, Serial No. 328,203

21 Claims. (Cl. 62—17)

The invention relates to railway rolling stock and more particularly to so-called "refrigerator cars" which are used to transport perishable commodities, such as vegetables, fruits, berries, frozen foods and fish. Such commodities must be maintained at a substantially even temperature to avoid decay. Heat or refrigeration is applied to the commodity while in transit depending upon the weather. Certain commodities (such as potatoes and oranges) generate heat and gases which must be removed by ventilation. A railway car, therefore, to haul perishable commodities must be arranged to cool, heat or ventilate the commodity while in the car. This applies, of course, if the car is running or standing still.

Various fruits, such as oranges, lemons and grapefruit from California and Florida, apples from Washington and Oregon, and various vegetables from such states as California, Colorado, Illinois and Georgia are loaded into the refrigerator cars and shipped; i.e., the cars actually start moving with destination unknown and without any consignee. To facilitate selling the commodity while enroute, grades for quality have been established. "Units" for volume have also been established by adoption of a standard size box for each fruit and the size of the fruit is designated by the number of that fruit in the box (which is stencilled on each box); the number of such boxes which can be loaded in a standard size refrigerator car is a "unit." To be more specific, the inside dimensions of a conventional end bunker refrigerator car are approximately 40 feet long, 8'3" wide and 7 feet high, and an ice bunker is positioned at each end of the car so that the loading space between the bunkers is about 33 feet. Such a car will hold and refrigerate 462 boxes of oranges or 420 boxes of lemons from California and such number of boxes constitutes a unit of the specific fruit of a known grade and size.

When the owner (usually through a cooperative association) sells his fruit, the shipment is diverted while enroute to the purchaser. It requires approximately seven days to transport fruit from California to Chicago; ten days to New York and twelve days to Boston; this system allows the owner to take advantage of changing market conditions. If the commodity is not sold enroute it is consigned to one of the several perishable commodity auction markets in the larger cities where it is sold before it becomes unusable.

A new type of refrigerator car has been de-

veloped by my assignee which is described and claimed in Bonsall Patent No. 2,136,999 of November 15, 1938, wherein the refrigerant containers are positioned adjacent the ceiling of the car with drip pans spaced therebelow. Air in the space below the refrigerant containers, being cooled by the refrigerant in the containers (preferably ice or ice and salt), flows through vertical flues into a space below a foraminous secondary flooring below the lading and coming into contact with the lading, is warmed thereby and rises to the space below the refrigerant container, where it is cooled by contact with the refrigerant and repeats the cycle. This is called lateral or cross-wise air circulation.

The Bonsall improved refrigerator car eliminates the necessity of the end ice bunkers, thus increasing the available lading space from 33 feet to 40 feet without increasing the train length or overall length of the car. Furthermore, in the conventional end bunker car, hereinbefore described, it is usually necessary to leave at least two feet between the top of the lading and the ceiling of the car for the warmed air to return to the end bunkers, whereas in Bonsall's top bunker car the lading can be loaded up to the ceiling, thus materially increasing the volume and weight of the lading without decreasing the efficiency of the refrigeration of the lading (in fact, tests show better refrigeration). Again to be specific: The conventional forty foot end bunker car holds 462 boxes of oranges (which is a unit for that particular fruit), whereas a Bonsall top bunker car was actually loaded and shipped with 840 boxes of oranges, or one and eight-tenths units. The sizes and weights of the boxes are commercially recognized standards.

One of the objects of the invention is to provide a refrigerator car that will hold and refrigerate more than an established unit of lading and which shall include means to segregate one unit from the remainder of the load so that said unit may be loaded and unloaded without disturbing the remainder of the load. The said remainder may be another unit.

Another object is to provide an insulated partition so that the commodities on opposite sides of the partition may be maintained at different temperatures.

Another object is to provide a partition which has both great strength and great resiliency so that a shifting lading within either compartment is protected from injury due to sliding with great impact against a rigid partition.

Another object of the invention is to adapt the

above-mentioned partition as a means to resist weaving of the car during service movements thereof. There is a tendency at certain times for a railway car to get out of square; i. e., for a plan view of the car to assume the shape of a parallelogram instead of a rectangle. The partition rigidly attached to the side walls and also possibly to the underframe and/or roof adds to the rigidity of the car.

A further object is to provide a hollow section post associated with each side wall of the car and to attach the partition to both of such posts. The hollow section post functions both to cause the partition to function as a semi-restrained beam and to prevent the side walls of the car from bowing toward each other when the partition is deflected under the impact of a shifting lading.

Another object is to insulate the above mentioned partition in such a way as to prevent the heat flow from one compartment to the other compartment. I accomplish this result by providing a continuous insulation blanket extending from the floor upwardly into the partition and in a similar manner blankets extending continuously from the roof downwardly into the partition and from each side wall inwardly into the partition.

The design of a refrigerator car having overhead refrigerant containers presents the problem of providing a support for the containers. In one type of car, such as that shown in Winship Patent No. 2,182,652 of December 5, 1939, the load supporting posts are disposed adjacent the interior of the car and are supported at their lower ends upon the underframe of the car by some insulating means, such as the pedestals of relatively small area shown in the above mentioned patent. In such a construction having inside posts, the posts are substantially at the temperature of the interior of the car and the refrigerant containers may therefore be attached directly thereto. In the construction disclosed in the instant case, I provide the load supporting posts adjacent the exterior of the car, in which position they have a temperature substantially that of the outside air. Such a construction permits a simpler and more rigid connection to the underframe of the car for the reason that such connection does not have to be insulated. From the upper parts of the outside posts I attach, by an insulating means hereinafter described, the refrigerant containers. I also suspend from the upper parts of the outside posts inner frame members and side flue members which are insulated from the outside posts. Means are provided to brace the lower parts of the inner frame members and side flue members against swinging in pendulum fashion.

Another object of the invention is to utilize the above mentioned insulated partition to at least partially support the refrigerant containers in the upper part of the car.

A still further object of the invention is to provide substantially continuous insulation blankets extending longitudinally of the car at the junctions of the floor and side walls; in other words, at the side sills.

Another object of the invention is to provide a continuous insulation blanket of substantially uniform thickness extending from the side wall of the car around the corner into the end wall of the car. A further object is to provide such corner construction so that the end lining and side lining are rigidly supported and secured to

the car structure, and a still further object is to provide means associated with the corner construction to hold the insulation in the intended position.

Another object is to use a corrugated plate as the principal structural member of the partition and to space the lower edge of the corrugated plate a substantial distance above the underframe of the car. The connection between such corrugated plate and the underframe is a member adapted to reduce heat flow between the underframe and the corrugated plate.

Other objects and advantages of my invention will be apparent from the following detailed description by referring to the accompanying drawings.

In the drawings:

Fig. 1 is a longitudinal vertical section through a refrigerator car embodying my invention.

Fig. 2 is a plan view of the car shown in Fig. 1, the lower half being a section through the side wall of the car below the refrigerant containers and the upper half being a plan view showing the construction with the roof removed.

Fig. 3 is a transverse section through the car shown in Figs. 1 and 2 having certain parts partially broken away to show the detailed construction.

Fig. 4 is an enlarged view of the lower left hand corner of Fig. 3.

Fig. 5 is a plan view on line 5—5 of Fig. 6 showing the connection of the partition to a side wall of the car.

Fig. 6 is an elevational view of the structure shown in Fig. 5.

Fig. 7 is a plan view on line 7—7 of Fig. 8 of a means to connect the inner side plate to an outer side post.

Fig. 8 is an elevational view of the structure shown in Fig. 7.

Fig. 9 is a view similar to Fig. 4 showing a modified construction.

Fig. 10 is a view similar to a part of Fig. 2 showing a modified form of partition.

Figs. 11 and 12 are views similar to parts of Figs. 3 and 1, respectively, showing a modified form of connection between the partition and the underframe, the floor insulation having been omitted from Fig. 11 for clarification.

Fig. 13 is a view similar to a part of Fig. 1 showing a modified connection of the partition to the roof of the car.

Fig. 14 is an enlarged view of a corner of the car shown in Fig. 2.

The general parts of the refrigerator car shown are insulated roof A; side walls B; end walls C; floor D; hatches E; refrigerant containers F; side wall flues G; foraminous floor rack H and space J between rack H and floor D. A refrigerant container F is positioned directly below the roof A and adjacent the side wall B. A drip pan K is provided below the container F and a partition L is secured in an upstanding position at the edge of the drip pan K. The drip pan K and partition L cooperate with the roof A and side wall B to form an enclosing structure M around the container F, an air inlet opening N being provided by spacing the partition L from the roof A. An air discharge opening P which leads to the flue G is formed by spacing the drip pan K from the wall B. Cars of this type commonly have a row of refrigerant containers F near each side wall B and spaced apart at the center of the car. The partitions L are also spaced apart to form a

duct Q which communicates between the lading chamber R and openings N.

Air circulation is as follows: Air in the lading chamber R is warmed by contact with the lading and rises through the duct Q to enter the enclosing structures M through the air inlet openings N. The air is cooled by contact with the refrigerant containers F and falls by reason of its greater density through the discharge openings P and flues G to the space J whence it rises through the rack H to the lading chamber R.

As shown most clearly in Fig. 3, the under-frame 2 of the car comprises a center sill 3 having laterally extending cross members 5, such as bolsters, cross bearers and cross ties. The side sills 6 are supported upon the outer ends of the various cross members 5 preferably by connecting pieces, such as the channel 8 shown at the left of Fig. 3, or the bulb angle 9 shown at the right of Fig. 3. Outer vertical side posts 11 and side sheathing 12 are secured in an upstanding position to each of the side sills 6, the side sheathing 12 being secured to the spaced apart posts 11. Outer side plates 14 are mounted upon the upper ends of the posts 11 and the outer roof structure 15 extends between and is supported by the outer side plates 14. The outer roof structure 15 preferably is comprised of a plurality of sheets 17 having upstanding flanges at their adjacent edges and carlines 18 in the form of inverted channels overlying the flanges of the roof sheets 17 and being secured thereto. At each corner of the car is an outer corner post 20 extending between and secured to the side plate 14 and side sill 6. The side sheathing 12 is secured to the corner post 20 and an end wall sheathing 21 extends between and is secured to the corner posts 20 at opposite sides of the car. Any type of corner post and end wall sheathing may be used, but a preferable construction embodies a type shown in patent to Jumper et al. No. 2,185,168 issued December 26, 1939.

The interior of the car is divided into two lading compartments 24 by a partition 25 extending between the side walls B of the car. The compartments 24 may be of equal or unequal size depending upon the use for which the car is intended. The principal structural member of the partition 25 is preferably a plate 27 having horizontally disposed corrugations 28 which extend substantially between the side walls B. The plate 27 shown in the drawing is similar to the end wall sheathing of the car, as shown in the above mentioned Jumper et al. patent. The posts 30 which function both as side wall structural members and as anchor members of the partition 25 are preferably hollow section members which may be formed, as at the corners of the car, by a W-shaped member 31 secured at one leg 33 thereof to the side wall sheathing 12 and to the flange 36 of the plate 27 and at the other leg 34 to the corrugated plate 27. The flange 36 is preferably jointed to the plate 27 by a curve 37 of relatively large radius and the corrugations 28 merge into the flanged part of the sheet. There is thus formed a structural member 30 at each end of the corrugated plate 27 which will cause said plate to deflect as a semi-restrained beam when the lading exerts a force upon the partition 25. The box section posts 30 are also relatively rigid and thereby prevent bowing in of the side walls B of the car when the partition 25 receives an impact. At the upper edge of the plate 27 there are two angles 35 arranged back to back on opposite sides of the

plate 27 and having their horizontal legs 38 extending laterally in opposite directions. The angles 36 are preferably attached to the outer side plates 14, as shown at 39 in Fig. 3. The lower edge of the corrugated plate 27 preferably has angles 40 arranged in a manner similar to the top angles 35, which lower angles are secured to the center sill 3 and side sills 6.

Fig. 10 shows a modified type of partition and the posts 42 in this modification are comprised of Z-bars 44 and angle bars 45 secured together. The plate 47 is formed with corrugations 48 which merge into the plane of the plate near the margins 50 thereof and the margins 50 are secured to the posts 42.

The lower edge of the plate 49 may be flanged (51), as shown in Figs. 11 and 12, and supported by a pedestal type bracket 53 secured to the center sill 3 of the car. This pedestal type bracket 53 is designed to have a relatively small area so as to prevent heat flow between the underframe 2 of the car and the plate 49, which heat flow would be undesirable in that it would tend to flow into the lading compartments 24. The bracket 53 may be hollow and may be filled with insulation 54. The flange 51 on the plate 49 is thus imbedded within the floor insulation 56 a substantial distance above the lower surface of the floor D and is, therefore, not materially affected by the outside temperature.

As shown in Fig. 13, the upper edge of the plate 58 may extend upwardly between the upstanding flanges of adjacent roof sheets 17. The inverted channel-shaped carline 18 thus overlies both the roof sheet flanges and the upper edge of the plate 58 and is secured thereto.

Inner side plates 63 are spaced inwardly from the outer side sheathing 12 a distance substantially that of the thickness of the walls B. The inner side plate 63 is preferably continuous between a corner post 20 of the car and the partition 25 and is formed of three sections. One section 64 extends between the corner post 20 and the door post nearest thereto. Another section 67 extends between the other door post 69 and the partition 25, and the third section 70 is inserted between the first mentioned sections 64, 67 and extends substantially between the door posts. The third section 70 may be reinforced by a splice member 72 which overlaps each of the first two mentioned sections 64, 67 and is secured thereto.

The door posts 75 are preferably Z-bars 76 extending between and secured to the outer side plate 14 and side sill 6. Wooden fillers 78 are preferably attached to the posts 75 to provide both insulation and seats for the doors. Angle clips 79 are secured to the upper ends of the fillers 78 and to the inner side plate 63 to provide a support for said inner side plate in the vicinity of the doorway.

The end of the inner side plate 63 adjacent the partition 25 is supported by a bracket assembly 81 shown in detail in Figs. 5 and 6. The upper bracket 84 on the left side of the plate 27 comprises a vertical leg 85 secured to the plate 27, a horizontal leg 87 extending laterally from the plate 27 and a web 88, triangular in the form shown, extending between the horizontal (87) and vertical (85) legs. The upper bracket 84 is supported by a lower bracket 90 of similar form, but inverted so that the horizontal leg 89 of the lower bracket 90 underlies the horizontal leg 87 of the upper bracket 84 in flatwise relation therewith. The vertical leg 91 of the lower bracket 90 is secured to the plate 27. A wooden block 93 re-

upon and is supported by the horizontal leg 87 of the upper bracket 84 and is secured thereto by the bolts 94. An angle clip 96 is secured by its vertical leg 87 to the inner side plate 63 and has its horizontal leg 99 overlying the wooden block 93 so as to support the side plate 63. The angle clip 96 may be secured to the inner side plate 63 by stud rivets 101 having bolts 102 on their ends for the purpose of securing the side plate 63 to the wooden block 93. The bracket assembly 104 on the right side of the plate 27 is similar to that heretofore described except that the web 105 is of somewhat different form and is secured by the rivets 106 to a leg 108 of the hollow section post 38. I have shown and described a wooden block 93, but I contemplate the use of any other rigid insulating material as a substitute for wood.

At the ends of the car the inner side plates 63 are secured to the corner posts 20 of the car. A short angle member 112 is secured to the corner post 20 by a vertical leg 113 with its horizontal leg projecting inwardly. A wooden block 115 rests upon the horizontal leg of the angle member 112 and is secured thereto. An angle clip 116 having an outwardly extending horizontal leg 118 overlies and rests upon the wooden block 115. Stud rivets 119 may be used to secure the angle clip 116 to the inner side plate 63 and to secure the inner side plate 63 to the wooden block 115, as described in reference to Figs. 5 and 6.

Refrigerator cars of this general construction may be built without the partition 25, in which case means should be provided to support the inner side plate 63 at desired positions along the length of the car. Supporting means suitable for this purpose is shown in Figs. 7 and 8. The post 123 shown in Figs. 7 and 8 is the conventional side wall post, such as is shown in Fig. 2. A bracket 124 having a vertical leg 126 is secured, preferably by rivets, to the web 127 of the post 123. The bracket 124 is provided with two horizontal legs, one (129) which overlies the post 123 to provide a further support and the other (130) which extends toward the interior of the car. A wooden block 132 rests upon the horizontal leg 130 and is secured thereto by some means, such as the bolt 133 shown. Triangular webs 135 may be provided to join the horizontal leg 130 with the vertical leg 126. The inner side plate 63 is provided with an angle clip 136 having an outwardly projecting horizontal leg 138 adapted to overlie and rest upon the wooden block 132. Stud rivets 139 and bolts 141 in combination may be used as described in reference to Figs. 5 and 6 to secure the clip 136 to the inner side plate 63 and to secure the inner side plate 63 to the wooden block 132. The construction shown in Figs. 7 and 8 may be used, if desired, to utilize certain of the outer posts 11 to provide additional supports for the inner side plate 63.

Any number and any type of refrigerant containers may be used in a car of this type. In the form shown there are four containers F in each compartment 24, two adjacent each side wall B with a duct Q therebetween at the longitudinal center of the car. Carlines 145 are disposed adjacent the ends of the containers F and extend between and are secured to the inner side plates 63. Any convenient means may be used to secure the carlines 145 to the inner side plates 63, such as the brackets 146 shown in Fig. 8, wherein one flange 148 is connected to the horizontal leg 149 of the inner side plate 63, another flange 151 is

connected to the vertical leg 152 of the inner side plate 63 and a third flange 154 provides an underlying support for the carline 145 to reinforce the rivets 155. Stud rivets 157 similar to those described in reference to Figs. 5 and 6 may be used, if desired, to secure the carline brackets 146 to the inner side plates 63, as shown in Figs. 7 and 8. Laterally extending brackets 158 are secured to the carlines 145 at predetermined positions between the ends thereof and are engaged by other brackets 160 extending outwardly from the ends of the containers F. The usual hatches E are provided for loading refrigerant into the containers F.

The floor D of the car is supported by longitudinally extending stringers 164 which extend between the cross members 5 of the under-frame 2 and are attached thereto by the brackets 165. The sub-floor 167, preferably ply-wood or a thin metallic sheet, rests upon the upper surface of the stringers 164. Insulation 168 is placed upon the sub-floor 167 and upper stringers 170 are placed upon the insulation 168 so as to compress said insulation the maximum distance, thereby providing a substantially incompressible material between the upper (170) and lower (164) stringers. The upper floor surface may be either wood covered with a waterproof fabric or steel sheets joined together by some suitable means, such as that shown in Bonsall Patent No. 2,189,126 of February 6, 1940. The floor rack 171 comprises stringers 173 extending transversely of the car and spaced apart slats 174 extending longitudinally of the car and secured to the upper surfaces of the stringers 173. A gutter 176 is provided at each side of the floor D to receive liquid from the refrigerant containers F, which liquid flows downwardly through the side wall flues G. If a metallic floor sheet 177 is used, the gutter 176 is preferably made of a metallic sheet separate from the floor sheet and connected thereto preferably by the weld 179.

Spaced apart inner frame members 183, which in the form shown are Z-bars, are suspended from the inner side plate 63. The inner frame members adjacent the partition 25 and at the corner of the car are preferably W-section members 184, 186. A plurality of metallic sheets 187 having outwardly projecting panels 189 formed therein are also suspended from the inner side plates 63. The sheets 187 extend between and are secured to the inner frame members 183. Means are provided to prevent the inner frame members 183 and the sheets 187 swinging pendulum fashion from the inner side plate 63. In the modification shown in Figs. 3 and 4, a belt rail 190 is secured to the lower parts of the outer posts 11 and extends therebetween. The lower parts of the frame members 183 are attached to the belt rail 190, preferably by the bolts 192. It is evident from Fig. 4 that the means associated with the belt rail 190 to connect the inner frame members 183 and the outer posts 11 is not intended to resist the vertical thrust but merely to prevent horizontal movement, the vertical loads being taken entirely at the upper ends of the inner frame members 183. The gutter 176 has an outwardly extending flange 193 and upwardly extending reflare 194 interposed between the inner frame members 183 and the belt rail 190.

The lower parts of the sheets 187 are secured to the gutter 176 by any suitable means, such as by the self-tapping screws 196. Side lining 197, preferably ply-wood or other form of wood, is attached to the inner frame members 183 in flat-

wise relation with the sheets 187, the side wall flues G being formed between the lining 197 and the outwardly projecting panels 189 in the sheets 187. Metallic veneer sheets 198 may be interposed between the lining 197 and the sheets 187.

In Fig. 9, a modified means is shown to prevent pendulum action of the inner frame members 183 and sheets 187. No belt rail is provided, but in place thereof straps 200 are secured to the lower parts of the inner frame members 183 and 10 also to the floor stringers 170, 164. It is pointed out that in a construction as shown in Fig. 9, a continuous insulation blanket 199 may extend from the floor D into the side wall B. There is thus no break in the insulation blanket and no 15 opportunity for heat leakage from the exterior of the car to the interior.

The outer corner post 20 is preferably a W-section member 203 having angularly disposed arms 205, 206. The inner corner post 207 is preferably a similar member having angularly disposed arms 209, 210 parallel respectively with the angularly disposed arms of the outer post and spaced therefrom. This permits an insulation blanket 212 to extend continuously from the side wall B of the car into the end wall C of the car, the space in which the blanket is confined being somewhat tortuous so as to hold said blanket in position. One of the arms 209 of the inner corner post 207 provides a backing for the side lining 197 and the flange 214 on the arm 209 of the inner corner post 207 provides a backing for the end lining 213.

The partition 25 is preferably formed of a plate 27 with horizontally disposed corrugations 28 and lining 217 disposed on each side of the plate 27 in spaced relation thereto so that an insulation blanket 218 may be placed between the plate 27 and each lining 217. Nailing strips 220 are preferably disposed in certain of the corrugations 28 to compress the insulation 218 therebetween, thereby holding said insulation in place and also to provide supports for the lining 217.

The ceiling 223 of the car extends only to the partition lining 217 thereby leaving a space between the ceiling 223 and the plate 27 so that a roof insulation blanket 224 may extend downwardly between the plate 27 and the partition lining 217 and/or so that a partition insulation blanket 226 may extend upwardly into the space between the ceiling 223 and the outer roof sheets 17. In a similar manner the floor 229 extends only to the partition lining 217 so that the insulation 230 may be continuous between the floor D and the partition 25. Also, at the side of the car, a space is provided between the side lining 197 and the plate 27 for the extension of an insulation blanket 233 continuously between the side wall B and the partition 25. It is apparent that the insulation of the partition 25 extends continuously into the insulation in the roof A, the floor D and both side walls B. This condition exists on each side of the partition 25 so that the two compartments 24 of the car are thereby well insulated from each other.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator car, a wall having spaced apart substantially vertical posts, a longitu-

dinally extending inner side plate spaced inwardly from the upper parts of said posts, insulating means arranged to secure said side plate to certain of said posts, spaced apart substantially vertical frame members suspended from said side plate, lining secured to said frame members and means to brace the lower ends of said frame members against lateral movements.

2. In a refrigerator car, a wall having spaced apart substantially vertical posts adjacent the exterior thereof, a longitudinally extending inner side plate spaced inwardly from the upper parts of said posts, means arranged to secure said side plate to one of said posts comprising a wooden block interposed between said side plate and said last mentioned post, a bracket secured to said last mentioned post which provides a substantially horizontal seat for said block and a member extending laterally from said side plate arranged to overlie said block, spaced apart substantially vertical frame members suspended from said side plate, lining secured to said frame members and means to brace the lower ends of said frame members against lateral movement.

3. In a refrigerator car, a wall having spaced apart substantially vertical posts, a floor comprising upper metallic floor sheets supported by subjacent stringers, a longitudinally extending inner side plate spaced inwardly from the upper parts of said posts, insulating means arranged to secure said side plate to certain of said posts, spaced apart substantially vertical frame members suspended from said side plate, lining secured to said frame members and means to brace the lower ends of said frame members against lateral movement comprising a longitudinally extending trough interposed between said frame members and said metallic floor sheets.

4. In a refrigerator car, a wall having spaced apart substantially vertical posts, a longitudinally extending inner side plate spaced inwardly from the upper parts of said posts, insulating means arranged to secure said side plate to certain of said posts, spaced apart substantially vertical frame members suspended from said side plate, lining secured to said frame members and means to brace the lower ends of said frame members against lateral movement comprising a longitudinally extending trough interposed between said frame members and said side plate.

5. In a refrigerator car, a wall having spaced apart substantially vertical posts, a floor, a longitudinally extending inner side plate spaced inwardly from the upper parts of said posts, insulating means arranged to secure said side plate to one of said posts, spaced apart substantially vertical frame members suspended from said side plate, a metallic sheet secured to said frame members, an outwardly projecting panel in said sheet, lining disposed in spaced relation to said panel to form a flue therebetween and means to brace the lower ends of said frame members against lateral movement.

6. In a refrigerator car, a wall having spaced apart substantially vertical posts, a longitudinally extending inner side plate spaced inwardly from the upper parts of said posts, insulating means arranged to secure said side plate to one of said posts, spaced apart substantially vertical frame members suspended from said side plate, lining secured to said frame members and means to brace the lower ends of said frame members against lateral movement comprising

ties extending between and secured to said frame members and said posts.

7. In a refrigerator car, spaced apart walls each comprising spaced apart posts and sheathing extending between and secured to said posts, a plate extending between said walls and secured at its opposite ends to certain of said posts, inner side plates spaced inwardly from said posts, insulating means associated with said certain posts arranged to provide supports for said side plates, spaced apart carlines extending between and secured to said side plates, a container adapted to receive a temperature changing medium disposed between said carlines and means associated with said carlines to support said container.

8. In a refrigerator car, spaced apart walls each comprising spaced apart posts and sheathing extending between and secured to said posts, inner side plates spaced inwardly from said posts, insulating means associated with some of said posts arranged to provide supports for said side plates, spaced apart carlines extending between and secured to said side plates, a container adapted to receive a temperature changing medium disposed between said carlines and means associated with said carlines to support said container.

9. In a refrigerator car, spaced apart walls each comprising spaced apart posts and sheathing extending between and secured to said posts, a plate having substantially horizontal corrugations formed therein extending between said walls and secured at its opposite ends to certain of said posts, said certain posts cooperating with parts of said plate to form hollow members into which said corrugations merge, inner side plates spaced inwardly from said posts, insulating means associated with said plate arranged to provide supports for said side plates, spaced apart carlines extending between and secured to said side plates, a container adapted to receive a temperature changing medium disposed between said carlines and means associated with said carlines to support said container.

10. In a refrigerator car, spaced apart walls each comprising spaced apart posts and sheathing extending between and secured to said posts, a plate having substantially horizontal corrugations formed therein extending between said walls and secured at its opposite ends to certain of said posts, said certain posts cooperating with parts of said plate to form hollow members into which said corrugations merge, inner side plates spaced inwardly from said posts, insulating means associated with said certain posts arranged to provide supports for said side plates and a container adapted to receive a temperature changing medium supported by said inner side plates.

11. In a refrigerator car, spaced apart walls each comprising spaced apart posts and sheathing extending between and secured to said posts, a plate extending between said walls and secured at its opposite ends to certain of said posts, inner side plates spaced inwardly from said posts, insulating means associated with said plate arranged to provide supports for said side plates and a container adapted to receive a temperature changing medium supported by said inner side plates.

12. In a refrigerator car, spaced apart walls each of said walls comprising spaced apart posts and outer sheathing secured to said posts, a plate extending between said walls and secured

70 at its opposite ends to certain of said posts, wall lining disposed in spaced relation to said sheathing, partition lining disposed in spaced relation to said plate and insulation between said partition lining and said plate, said insulation extending continuously into the space between said sheathing and said wall lining.

13. In a refrigerator car, spaced apart walls each of said walls comprising spaced apart posts and outer sheathing secured to said posts, a plate extending between said walls and secured at its opposite ends to certain of said posts, wall lining disposed in spaced relation to said sheathing, partition lining disposed in spaced relation to said plate on both sides thereof and insulation between said partition lining and said plate on both sides thereof, said insulation extending continuously into the space between said sheathing and said wall lining.

14. In a refrigerator car, spaced apart walls each of said walls comprising spaced apart posts and outer sheathing secured to said posts, and a corrugated metallic plate extending between said walls and secured at its opposite ends to certain of said posts, said certain posts cooperating with parts of said plate to form hollow members into which the corrugations of said plate merge.

15. In a refrigerator car, spaced apart walls each of said walls comprising spaced apart posts and outer sheathing secured to said posts, a corrugated metallic plate extending between said walls and secured at its opposite ends to certain of said posts, wall lining disposed in spaced relation to said sheathing, partition lining disposed in spaced relation to said plate and insulation between said partition lining and said plate, said insulation extending continuously into the space between said sheathing and said wall lining, said certain posts cooperating with parts of said plate to form hollow members into which the corrugations of said plate merge.

16. In a refrigerator car, a hollow substantially vertical outer frame member, sheathing secured to the outer side of said frame member, an inner frame member disposed parallel with the outer frame member, at least part of the inner surface of the outer frame member and at least part of the outer surface of the inner frame member being substantially complementary and spaced apart substantially equal distances at all parts of said complementary surfaces, and insulation of substantially uniform thickness disposed between said frame members.

17. In a refrigerator car having spaced apart walls, a plate extending between said walls, the opposite edges of said plate flanged on curves of relatively large radius with the flanges secured flatwise to said walls, a post member having singularly disposed legs associated with each of said opposite edges, one of said legs secured to said flange and the other of said legs secured to the body part of the plate, and substantially horizontal corrugations formed in said plate merging at their opposite ends into said flanges.

18. In a refrigerator car having spaced apart walls, a longitudinally extending structural member adjacent each of said walls, insulating means arranged to secure said members to the respective walls, spaced apart carlines extending between and secured to said members, refrigerant containers between said carlines, and means to attach said containers to said carlines.

19. In a refrigerator car, an insulated wall including a plurality of posts disposed adjacent

the exterior of said wall, brackets carried by certain of said posts and including inwardly projecting legs, refrigerant containers, and means to support said containers including wood means resting upon said legs, and outwardly projecting legs overlying and supported by said wood means.

20. In a refrigerator car, an insulated wall including a plurality of posts disposed adjacent the exterior of said wall, brackets carried by certain of said posts and including inwardly projecting legs, refrigerant containers, and means to support said containers including insulating and supporting means resting upon said legs, and out-

wardly projecting legs overlying and supported by said insulating and supporting means.

21. In a refrigerator car, an insulated wall including a plurality of posts disposed adjacent the exterior of said wall, brackets carried by certain of said posts and including inwardly projecting legs, refrigerant containers, and means to support said containers including wood means resting upon said legs, and outwardly projecting legs overlying and supported by said wood means, said legs having relatively large area to decrease unit bearing pressure upon said wood means.

KURT E. ZEIDLER.
